DESIGN FOR A COMBINED HANDLE AND LID FOR CONTAINERS

Harper J. Ransburg, Indianapolis, Ind.

Application March 11, 1936, Serial No. 61,574

Term of patent 7 years

To all whom it may concern:

Be it known that I, Harper J. Ransburg, a citizen of the United States and a resident of Indianapolis, county of Marion, and State of Indiana, have invented a new, original, and ornamental Design for a Combined Handle and Lid for Containers, of which the following is a specification, reference being had to the accompanying drawing, forming part thereof.

In the drawing, Fig. 1 is a perspective view of a combined handle and lid for containers, showing my new design; and Fig. 2 is a top plan view thereof.

I claim:

The ornamental design for a combined handle and lid for containers, as shown.

HARPER J. RANSBURG.
